LINE HANGER

Jerome C. Kniedler, Pittsburgh, Pa.

Application May 7, 1935, Serial No. 20,269

1 Claim. (Cl. 68—3)

The present invention relates to clothes line hangers, and the main object is to provide means of a simple, efficient and practical nature for supporting clothes lines and the like whereby said lines may be disposed, for instance, in basements, 5 cellars and the like in a sturdy manner, the apparatus being inexpensive to manufacture, strong, and durable.

With the above and numerous other objects in view as will appear as the description proceeds, 10 the invention consists in certain novel features of construction, and in the combination and arrangement of parts as will be hereinafter more fully described and claimed.

15 In the drawings:

Figure 1 represents a bottom plan view of an apparatus embodying the features of my invention.

Figure 2 represents an end elevation thereof.

20 Figure 3 represents a perspective view of one end member.

Figure 4 is a perspective view of the angle iron from which an end member is formed.

25 Figure 5 is an enlarged detail section taken substantially on the line 5—5 of Figure 2.

Referring to the drawings in detail, it will be seen that there are two end members which are identical in construction and I shall now proceed to describe one in detail. Each end member is 30 formed from a single angle iron bar as shown in Figure 4, one flange is provided with two slits 5 spaced equally from the center of the bar so that the flanges may be bent inwardly and the end portions of the bars bent upwardly to a right 35 angular position with respect to the center portion or horizontal portion, I have denoted the horizontal and central portion by the letter A and the upright or end portions by the letters B—B. It is to be noted that the aforementioned flange 40 in the horizontal portion A is provided with a plurality of notches 6. It is to be noted that the extremities of the portions B have the other flange provided with a relatively short slit or split so that a portion may be bent outwardly at right angles

to form ears 8. As illustrated to advantage in Figure 2 it will be seen that the upper extremities of these portions B are nailed, screwed or otherwise fastened to a joist, the ears 8 being under the joist while the other portions of the 5 extremities being alongside of the joist.

Numeral 9 denotes the clothes line. It will be seen that an end may be knotted and placed in one of the notches 6 and then run back and forth through the remaining notches and terminating 10 in a knot at the last notch thereby providing a plurality of spaced parallel strands on the clothes line.

It is thought that the construction, utility and 15 advantages of the invention will now be quite apparent to those skilled in this art without a more detailed description thereof.

The present embodiment has been described in detail since in actual practice it attains the features of advantage enumerated as desirable in 20 the statement of the invention and the above description. It will be apparent that numerous changes in the details of construction, and in the combination and arrangement of parts may be 25 resorted to without departing from the spirit or scope of the invention as hereinafter claimed or sacrificing any of its advantages.

Having thus described the invention, what is 30 claimed as new is:

A clothes hanger, comprising a pair of spaced 35 members, each of which is formed of a single bar of angle iron bent to provide a cross-piece, and upstanding end pieces, one of the flanges of the cross piece being vertically arranged and the other flange of the cross-piece extending toward the other member and with the lower ends of the end pieces resting on the ends of the last mentioned flange, the vertical flange of each cross piece having spaced notches therein opening out through the upper edge of said flange, and a 40 clothes line laced through the notches of the pair of cross pieces and providing runners in the line extending parallel with each other.

JEROME C. KNIEDLER.
